WILLIAM DUCHEMIN, OF BOSTON, MASSACHUSETTS, ASSIGNOR TO GEORGE B. BIGELOW, TRUSTEE.

Letters Patent No. 102,786, dated May 10, 1870.

IMPROVED METHOD OF MAKING TURNED SEWED SHOES.

The Schedule referred to in these Letters Patent and making part of the same.

To all whom it may concern:

I, WILLIAM DUCHEMIN, of Boston, in the county of Suffolk, and State of Massachusetts, have invented a new Method of Making Turned Sewed Shoes, of which the following is a specification.

Nature and Object of the Invention.

It relates to that class of shoes in which the sole is grooved or channeled upon its inner or flesh side, in such manner as to form a lip or rib, to which the upper is sewed while the shoe is wrong side out, and consists in lasting the shoe inside out, then removing it from the last, then sewing it on a machine, and afterwards turning it; the object being to make better machine-sewed work than has heretofore been done, and to do the same in an economical manner, for the following reasons, viz:

The sole of the shoe being in temper at the time of sewing, the tension of a sewing-machine can act more readily and effectively when the last has been withdrawn.

The feed-mechanism can also be so arranged that, when the last has been removed, less skilled labor is required to manipulate the shoe while in the process of being sewed by machinery.

Description of the Accompanying Drawings.

Figure 1 is a perspective view of a shoe.

Figure 2 is a plan, showing the bottom of the shoe as it appears before being turned.

Figure 3 shows a part of the sole and upper in section.

General Description.

In manufacturing my shoe, I take a sole which has been prepared with a groove or channel upon its inner or flesh side, and place it upon a last with the bottom or outside of the sole next to the last; then place the upper upon the last, and secure it to the sole in such manner that the last can be removed before the shoe is sewed. I then remove the last, and sew the upper to the sole, after which the shoe is turned and finished in the usual manner.

In temporarily securing the upper to the sole before removing the last, I usually prefer the following method—that is, attaching the upper to the lip or rib on the sole by means of sharp pins or pegs, which pass through said lip, as represented in the drawings, but which do not puncture the outer face or bottom of the sole.

I claim as my invention—

The herein-described method of making a turned shoe having a sole which has been channeled or grooved upon its inner or flesh side, to wit, by attaching the upper to the sole in the manner herein described, so that the last can be removed before sewing, then removing the last, sewing, and turning, substantially as set forth.
